UNITED STATES PATENT OFFICE.

HAROLD G. WAAR, OF CHICAGO, ILLINOIS, ASSIGNOR TO THE P. & M. CO., OF CHICAGO, ILLINOIS, A CORPORATION OF ILLINOIS.

TIE-SPACER FULCRUM.

1,278,532.

Specification of Letters Patent. Patented Sept. 10, 1918.

Application filed December 31, 1915. Serial No. 69,534.

To all whom it may concern:

Be it known that I, HAROLD G. WAAR, a citizen of the United States, residing at Chicago, in the county of Cook and State of Illinois, have invented a certain new and useful Improvement in Tie-Spacer Fulcrums, of which the following is a full, clear, concise, and exact description.

My invention relates to improvements in tie spacer fulcrums.

The objects of the invention are, to provide an improved device of this character having rounded, rail-engaging surfaces, thereby avoiding sharp edges which wear away in service and decrease the useful life of the device; to provide a device which may be applied to the base of the rail as distinguished from the head, but which provides, nevertheless, a fulcrum sufficiently high to give the desired leverage ratio; to provide a device devoid of local weaknesses developed in shrinking after casting the same, and to provide a device of generally improved design and convenience in use.

In the accompanying drawings, I have illustrated two structures which embody the invention. Other forms of the invention may be devised however.

Figure 1 is a top plan view of one form of device.

Fig. 2 is a side elevation thereof.

Fig. 3 is an end elevation of a modified form of device showing the relation thereof to the rail, cross-tie and crow-bar.

Fig. 4 is a top plan view of said second form of device.

Cast metal, preferably malleable iron, is employed in the manufacture of the two forms of the invention illustrated, although with modified constructions, the device may be made of other material. It is applied to the rail 1 adjacent to a cross tie 2, about as shown in Fig. 3. A flat transverse portion 3 lies against the base of the rail and has a pair of vertical curved walls 4, 5 projecting upwardly therefrom, between which the rail base is received. The wall 4 is provided with an overhanging lip or flange 6 forming a jaw which fits loosely over the rail base, the angle of the jaw being somewhat greater than the angle of the corresponding section of the rail base to permit the device to tilt somewhat in applying it to the rail base. The remainder of the device extends later-

ally and upwardly and is designated generally by reference 7. It is reinforced by suitable upper and lower flanges 8, 9. These flanges are quite deep about the middle of the device, but the lower ones in particular taper toward opposite ends of the device, 60 tapering off more along the half beneath the rail base than along the half which projects upwardly beside the rail. It will thus be seen that said projecting half is heavier than the half beneath the rail base, and although 65 the device may have a slight pivotal movement in a vertical plane about the point 10, it tends to remain in the position shown in Fig. 2 for example, since the weight of the half to the left of said pivot causes an upward reaction in the half to the right of said pivot.

In the form shown in Figs. 1 and 2, the upper projection 7 has two vertical walls 11 thereon used as fulcrum surfaces, against 75 which a crow bar or other lever may be applied. These surfaces are inclined somewhat from a vertical plane and each terminates in a projecting shoulder or lug 12 forming an abutment for the crow bar or 80 other lever.

In the form shown in Figs. 3 and 4, only a single vertical inclined surface 13 and corresponding abutment 14 are provided. In other respects however, the construction is 85 substantially the same.

In either case the device is applied to the rail by first slipping the jaw over one flange of the rail and then tilting the device to raise the wall 5 into engagement with the 90 other side of the rail base and bring the base plate 3 against the bottom of the rail. The device as a whole being substantially at right angles to the rail, may be applied as close to the tie as may be desired, whereas, 95 with certain prior art devices requiring application thereof in a skewed position, it has been necessary to drive the device along the rail toward the tie after it has been applied.

When a lever 15 is applied to the fulcrum surface, as shown in Fig. 3, for the purpose of moving a tie laterally (the spikes having previously been withdrawn), the device as a whole is shifted around slightly in a horizontal plane to about the position shown in Fig. 4, whereupon the rail base is gripped between the curved walls 4, 5, and the device

held firmly thereon without slipping. In this position, the fulcrum surface is substantially at right angles to the longitudinal axis of the rail, thereby providing a satisfactory fulcrum for the lever. Since the device skews a different amount however, for rails of different sizes, the fulcrum surface will not always be exactly at right angles to said rail and therefore the abutments 12, 14 are provided to prevent the crow bar from slipping off the end. However, it will be noted that regardless of the extent of the skewing, the curved walls 4, 5 will always grip the the rail base between surfaces substantially parallel thereto at the point of contact; that is, surfaces of somewhat extended area as distinguished from gripping it between sharp corners. In certain prior devices, the skewing of the tie spacer fulcrum results in the rail being gripped between a pair of corners which in course of time wear away, thereby causing the device to skew at an increasing angle, and eventually causing it to be discarded. With the present construction, the wear is very gradual and is distributed so that the useful life of the device is materially increased.

In using the device as a fulcrum, it operates equally well regardless of which side the pressure is applied to; that is to say, it grips the rail equally well whether skewed on the rail in one direction or the other. In the first form of device, two fulcrum surfaces are provided whereby a tie may be moved either way by applying the lever to either side of the fulcrum structure. In the second form of device, only a single surface is provided.

Difficulty has also been experienced heretofore where the tie spacer fulcrum has been made of cast metal, in that the device would crack or break at or near the middle, when a powerful leverage was applied to it. The thickness of the metal necessitated by the great bending moment applied to this point, resulted in strains developed by shrinking of the metal after casting it, as a result of which local weakness developed, causing the device to break. In the present case, this disadvantage is obviated by the proportioning of parts disclosed, wherein the metal is of substantially uniform thickness at all points, and at the same time the vertical

depth of the flanges is ample to withstand the greatest bending moment.

Other disadvantages of prior devices has been that the fulcrum was too low, particularly where the device was applied to the base of the rail. Some attempts to obviate this have been made by applying the device to the head of the rail, but such practice is objected to by the railroads. In the present device, the fulcrums are at a considerable elevation above the top of the tie, whereby the desired leverage ratio is obtained.

When the device is applied to rails of different sizes, there is not only a variation in the amount of skewing as previously stated, but the variation in the vertical thickness of the rail flanges at the sides of the rail base results in tilting the device somewhat in a vertical plane. In Fig. 2 where the rail may be assumed to be of maximum thickness in its flanges, the transverse element 3 is horizontal, but if the rail were of less thickness, said element would incline downwardly to the left somewhat, providing a clearance beneath the left hand side of the rail base, since the device is supported on the rail at the point 10.

Various changes may be made in the structures illustrated without departing from the spirit of the invention.

What I claim as new and desire to secure by Letters Patent of the United States is:

1. A device of the class described, comprising a transverse element having a pair of vertical curved walls thereon arranged to receive the base of a rail between them and an extension thereon adapted to project to one side of the rail, said extension providing a fulcrum.

2. A device of the class described, comprising a casting having means for supporting it on the flange of a rail and being provided with deep reinforcing flanges on its under side, said flanges tapering toward opposite ends of said casting, the taper at one end being less than at the other end to make one half of the casting heavier than the other, said heavier portion being adapted to extend to one side of the rail base to keep the device in operative position thereon.

In witness whereof, I, hereunto subscribe my name this 29th day of December, A. D. 1915.

HAROLD G. WARR.
